Inventor:

J. S. Gray,

UNITED STATES PATENT OFFICE.

JOHN S. GRAY, OF NEW YORK, N. Y.

DOOR-SPRING.

Specification of Letters Patent No. 22,554, dated January 11, 1859.

To all whom it may concern:

Be it known that I, JOHN S. GRAY, of the city, county, and State of New York, have invented certain Improved Devices in Attaching and Straining Torsion Hinges for Doors, &c.; and I do hereby declare and ascertain my said invention, referring to the accompanying drawing, in which—

Figure 1, is a perspective view of the 10 socket and hinge combined. Fig. 2, is a bracket independent of the hinge; Fig. 3, turning bolt.

My improved spring is designed to combine convenience of arrangement with facility of operation and a permanence in the construction and application together with cheapness of cost greater than I have heretofore known in devices for the same purpose.

The construction is as follows: A socket *a* 20 has an extension plate *b* cast with it as seen in Fig. 2. In this socket there is a turning bolt *c* (shown detached in Fig. 3). This bolt has a square hole *e* in its upper end at its center, into which the end of the spring *d* 25 fits. The exterior form of this end of the bolt *c* is a hexagonal or some other polygonal prism, and below it is enlarged and of any figure. Through this part I make oblong holes *h* such as an ordinary screw 30 driver or similar instrument will readily

enter by which the bolt can be revolved in straining the spring either way.

f is a hold-fast and consists of a collar that just fits over the upper end of the bolt *c* and a tang that projects from it and resting 35 against the door frame or post prevents the bolt from revolving. When the bolt is to be turned by a screw driver as above named this socket is raised from the bolt as seen in Fig. 2, and after the bolt is turned it is re- 40 placed as indicated by red lines in the same figure. It will be noticed that the hold-fast *f* cannot be lost or mislaid as it is always connected with the spring when the parts are once in place by screwing plate *b* of 45 socket *a* to the door frame. Instead of forming the socket as in Fig. 2, this part may form one section of a butt hinge as in Fig. 1, the bolt *c* being the pivot.

Having thus fully described my improvement what I claim and desire to secure by Letters Patent is—

The combination of the socket *a*, *b*, bolt *c* and hold-fast *f* with the torsion spring constructed and arranged substantially in the 55 manner and for the purposes set forth.

JOHN S. GRAY.
